US0D1051565S

(12) **United States Design Patent** (10) **Patent No.:** **US D1,051,565 S**
(45) **Date of Patent:** **** Nov. 19, 2024**

(54) **BOOT**

(71) Applicant: **LaCrosse Footwear, Inc.**, Portland, OR (US)

(72) Inventor: **Ryan James Foust**, Portland, OR (US)

(73) Assignee: **LaCrosse Footwear, Inc.**, Portland, OR (US)

(**) Term: **15 Years**

(21) Appl. No.: **29/878,469**

(22) Filed: **Jun. 21, 2023**

Related U.S. Application Data

(63) Continuation of application No. 29/863,308, filed on Dec. 16, 2022, now Pat. No. Des. 990,833, which is a continuation of application No. 29/793,026, filed on May 26, 2021, now Pat. No. Des. 975,972, which is a continuation of application No. 29/764,906, filed on Jan. 4, 2021, now Pat. No. Des. 922,739, which is a continuation of application No. 29/691,208, filed on May 14, 2019, now Pat. No. Des. 908,322.

(57)

CLAIM

The ornamental design for the boot as shown and described.

DESCRIPTION

FIG. 1 is an isometric view of a boot showing the new design.

FIG. 2 is a right-side view thereof.

FIG. 3 is a left-side view thereof.

FIG. 4 is a front view thereof.

FIG. 5 is a rear view thereof.

FIG. 6 is a top view thereof; and

FIG. 7 is a bottom view thereof.

The broken lines in the drawings represent portions of the boot that forms no part of the claim.

1 Claim, 7 Drawing Sheets
